UNITED STATES PATENT OFFICE.

GEORGE X. WENDLING, OF SAN FRANCISCO, CALIFORNIA.

FOLDABLE SHIPPING BOX.

Application filed May 27, 1922. Serial No. 564,071.

To all whom it may concern:

Be it known that I, GEORGE X. WENDLING, a citizen of the United States, residing at the city and county of San Francisco and 5 State of California, have invented certain new and useful Improvements in Foldable Shipping Boxes, of which the following is a specification.

The present invention relates to a foldable shipping box adapted for delivery of the container in collapsed form, ready for assembling.

The invention has for its principal objects to provide a veneer collapsible or foldable box construction wherein the center of the box is longitudinally reinforced, affording a means for securing the top and bottom closure members in position, and at the same time forming compartments within the box; to provide a construction which is adapted for receiving smaller boxes or baskets of berries or citrus fruit, such as oranges, for the shipping thereof to market at small cost. Another object is to provide a construction wherein the contents of the receptacle is afforded ventilation, both at the top and bottom, even in single packages or when a multiplicity thereof are secured in stacked relation. Among the other objects of this 20 invention are to provide a shipping box capable of being cheaply constructed and which may be either returned to the shipper or may be destroyed by the consumer without any considerable loss; one which is light 25 in weight, thereby requiring but little charge in the handing thereof by express and one wherein the end walls of the box are secured midway of their length to the ends of the strengthening member or center brace and one wherein the top and bottom wall forming flaps are closed in overlapped relation and are retained in such manner by a securing batten.

With the above mentioned and other objects in view, the invention consists in the novel construction and combination of parts hereinafter described, illustrated in the accompanying drawings and pointed out in the claims hereto appended; it being understood that various changes in the form, proportion, size and minor details of construction within the scope of the claims may be resorted to without departing from the spirit or sacrificing any of the advantages 50 of the invention.

To more clearly comprehend the inven-

tion, reference is directed to the accompanying drawings, wherein—

Fig. 1 is a view in bottom elevation of the shipping box with several of the compartment boxes received within one compartment upside down and preparatory to closing the bottom forming flaps. 60

Fig. 2 is a transverse central sectional view disclosing the compartment boxes in 65 position and the bottom forming flaps in overlapping closed relation.

Fig. 3 is a view in perspective of one of the compartment boxes.

Fig. 4 is a view in elevation of the box 70 with the compartment boxes therein, illustrating the bottom closure forming flaps in closed position, and the box in a condition to be filled.

Fig. 5 is an end view of the box with the 75 top and bottom wall forming flaps in overlapped closed relation.

Fig. 6 is a view in end elevation of a tier 80 of boxes tied together, illustrating the ventilating and air circulating openings.

Fig. 7 is a view in perspective of one of the boxes, illustrating particularly the cover flap retaining batten.

Fig. 8 is a view in perspective of the 85 box in its collapsed condition.

Referring more particularly to the several views of the drawings wherein like characters of reference designate corresponding parts, 1, in the construction of this package, is a strip of material preferably of 90 veneer board, and is scored transversely at spaced points 2 to provide interconnected receptacle side and end walls 3 and 4. The terminal ends of the strip are then overlapped as at 5, Figure 7, and are secured 95 together in any suitable manner, the strip at this time forming a rectangular open frame structure. Secured to the inner faces of opposing side walls 3 are the sheets 6 of a width coextensive with the length of 100 the side wall, and of a length slightly greater than twice the width of the frame plus the depth of the side wall. These respective sheets are secured in position by suitable attaching means as staples 7, which if desired may also unite the terminal ends of the strip 1. At points slightly above and below the longitudinal edges of the side walls, the sheets 6 are longitudinally 105 scored as at 8, providing closure flaps 9 and 10, these flaps each being of a length 110 slightly greater than one half of the width

of the completed carton or receptacle, so that when the same are folded down to form a wall, their free ends will overlap as at 10', Figure 2 of the drawings. It will be observed that the strip scored to form side and end walls and the sheets affording the flaps for providing top and bottom wall closures are capable of being collapsed to form a substantially flat structure, as in Figure 8 and in assembling the box or container the frame forming strip is assembled as in Figure 1 and a brace 11 corresponding with the depth of the strip 1 and of the length of the receptacle is positioned between the end walls 4 to divide the receptacle into two compartments 12, and said brace is preferably nailed at its ends to the end walls 4 by the nails 13. This brace affords a rigid structure extending longitudinally 20 of the center of the container and also separates the container into two compartments.

In the particular embodiment of this invention illustrated, I have disclosed a box or container of a size to accommodate six compartment boxes of the type adapted for shipping strawberries or other small berries, but it is to be understood that the compartment box may be of such size and number corresponding to the size of the container 30 that said compartment box may contain such fruits or vegetables as desired, particularly oranges, grape fruit, grapes, tomatoes, and like fruits, and vegetables of a relatively large size. In assembling the 35 structure, a plurality of compartment boxes 14 are positioned in close formation within each compartment 12 with their open tops downwardly disposed as illustrated in Figure 1. After each compartment is supplied, the bottom forming flaps 9 are folded downwardly on their scores 8 with their free edges in overlapping relation as at 10' overlying one edge of the brace 11. A batten 15 is positioned longitudinally over 45 this edge of the brace 11 to overlie said overlapping ends and the same is secured to the brace by nails 16 which pass, through the batten, through the overlapping edges of the flaps and into the brace 11. The bottom of this container has now been formed and the container is reversed from the position in Figure 1 to that in Figure 4, wherein the compartment boxes are presented with their open tops upwardly disposed. 50 The compartment boxes are then supplied with their contents in any suitable manner and the top cover forming flaps 10 are folded down with their free edges in overlapping relation as were the bottom forming flaps 9, and such overlapping edges of the top forming flaps 10 are secured to the opposite edge of the brace 11 by nails which pass through a retaining batten 17. It will be observed that, in providing the scores 8 55 which form the flaps 9 and 10, the same are

disposed a slight distance removed from the opposing edges of the strip thus affording air circulation or ventilating spaces 18 at opposite ends of the receptacle or container at opposite sides and in connection with both the top and bottom thereof, which spaces afford ample ventilation and air circulation for the contents of the receptacle or container. This construction also enables the stacking of the receptacles or containers, as in Fig. 6, as by raising the edges to provide the air spaces 18, and by utilizing battens of veneer material, the co-operating battens of adjacent stacked receptacles or containers are disposed to contact when the 60 scored edges of the sheets of the stacked receptacles or containers rest on one another. In stacking the receptacles or containers as in Figure 6, the same are held in a unit package preferably by end battens 19 disposed in longitudinal alignment with the braces 11 and secured to the ends of the braces by nails 20.

It will be observed that I have provided a construction which is capable of being shipped in a knocked down condition semi-assembled, and that the same is adapted for ready assembling in the field or packing house or other place where it is desired to be filled, and that when assembled and closed is of a rigid structure, as the top and bottom wall forming flaps which extend in overlapping relation half the distance across the container are secured to the opposite edges of the brace, which brace is in turn united to the end walls of the container. It will be observed that the brace which extends longitudinally of the receptacle or container is secured to the walls of the container at both its edges and ends, not at one point but at a plurality of points thereby affording maximum strength to the container.

Having thus described my invention, what I claim as new and desire to protect by Letters Patent of the United States is:—

1. A container including connected side and end walls adapted for positioning to form a substantially rectangular frame, top and bottom wall forming flaps hinged at one edge with their free edges free to fold toward each other into meeting relation, a part extending across the interior of the frame and secured at its ends to opposing wall members, and means for securing the free edges of said top and bottom wall forming members to opposite edges of said part.

2. A foldable shipping box comprising 125 articulate side and end walls foldable one onto another and adapted for unfolding to form a substantially rectangular frame, top and bottom wall forming flaps projecting beyond opposing edges of opposing wall members and hinged to permit their free 130

edges to fold over the top and bottom of the frame toward each other into substantially meeting relation, a part extending across the interior of the frame and secured at its ends to opposing wall members, and means for securing the free edges of said top and bottom wall forming members to opposite edges of said part.

3. A collapsible shipping container comprising complementary side and end walls articulately connected and capable of forming a rectangular wall structure when moved from their collapsed positions, top and bottom wall forming members hinged to opposite walls of the container, said members comprising complementary wall forming portions projecting beyond the sides of the frame forming walls and foldable toward each other with the free edges of opposing portions in meeting relation to form a complete wall, a part extending across the wall structure and secured at its opposite ends to opposing walls, complementary top and bottom wall forming members hinged to opposite edges of opposing wall forming members, a longitudinal brace within the container, and means for securing the free edges of the complementary top and bottom wall forming members thereto.

4. A collapsible shipping container comprising complementary side and end walls articulately connected and capable of forming a rectangular wall structure when moved from their collapsed positions, top and bottom wall forming members hinged to opposite walls of the container, said members comprising complementary wall forming portions projecting beyond the sides of the frame forming walls and foldable toward each other with the free edges of opposing portions in meeting relation to form a complete wall, a part extending across the wall structure and secured at its opposite ends to opposing walls, and means for securing the complementary top and bottom wall forming members to said part.

5. A collapsible shipping container comprising complementary side and end walls articulately connected and capable of forming a rectangular wall structure when moved from their collapsed positions, top and bottom wall forming members secured to opposite walls of the structure, said members each comprising complementary portions adapted for folding toward each other into co-operating relation and each extending approximately one-half of the distance across the wall structure, a part extending transversely of the wall structure and over which the free edges of said complementary top and bottom wall forming members are adapted to overlap, and means for securing said part to said end walls and to said overlapping complementary top and bottom wall forming members.

6. A collapsible shipping container com-

prising complementary side and end walls articulately connected and capable of forming a rectangular wall structure when moved from their collapsed positions, top and bottom wall forming members hinged to opposite walls of the container, said members comprising complementary wall forming portions projecting beyond the sides of the frame forming walls and foldable toward each other with the free edges of opposing portions in meeting relation to form a complete wall, a part extending across the wall structure and secured at its opposite ends to opposing walls, complementary top and bottom wall forming members hinged to opposite edges of opposing wall forming members, a longitudinal brace within the container, and means for securing the free edges of the complementary top and bottom wall forming members thereto.

7. A collapsible shipping container comprising complementary side and end walls articulately connected and capable of forming a rectangular wall structure when moved from their collapsed positions, top and bottom wall forming members hinged to opposite walls of the container, said members comprising complementary wall forming portions projecting beyond the sides of the frame forming walls and foldable toward each other with the free edges of opposing portions in meeting relation to form a complete wall, a part extending across the wall structure and secured at its opposite ends to opposing walls, complementary top and bottom wall forming members hinged to opposite edges of opposing wall forming members and adapted for folding toward each other in overlapping relation, a brace extending between opposing walls of said structure and dividing the same into duplicate chambers, one adapted for closing by each of said complementary members, means for securing the ends of the brace to said end wall forming members, and means including nails and battens for securing the overlapping edges of complementary top and bottom wall folding members to said brace.

8. A shipping container comprising connected side and end walls forming a rectangular wall structure, complementary top and bottom closure forming members hinged at corresponding edges of said side walls to enable complementary members to fold toward each other and the free edges to overlap, a brace within said rectangular structure dividing the same into duplicate compartments one face of each of which is closed by one of said complementary members, and means for securing the free edges of said complementary top and bottom closure members and the structure end walls to said brace.

9. A shipping container comprising side

and end wall forming members assembled to form a rectangular wall structure, top and bottom pairs of closure flaps secured to the side wall members and hinged to swing relatively thereto at a point exteriorly of their outer edges, a brace within said wall structure dividing the same into duplicate compartments and over the opposite edges of which the free edges of said flaps are adapted to overlap when hinged to closed position, a batten overlying the overlapping seam of said flaps and extending longitudinally of the brace with its surface approximately flush with the hinged joints of said flaps, and means extending through the overlapping flaps and batten for securing said batten to the brace.

10. A shipping container comprising a strip scored transversely to form complementary end and side wall members adapted to form a rectangular container wall structure when the strip ends are united, a pair of container top and bottom wall forming

members, one associated with opposing wall structure members and each comprising a sheet scored parallel with the opposite side edges of its associated wall structure providing each sheet with a pair of terminal closure flaps, one projecting beyond each face of the container and each coextensive with the length of the container and of a width slightly greater than one-half the width thereof, a brace removably positioned longitudinally within the container wall structure with its ends in contact with the structure end walls and its edges substantially flush with the edges of the structure end walls, the free ends of said flaps adapted for folding into overlapping relation with opposing edges of said brace, and means for securing the edges of said flaps and said wall structure ends to said brace.

In testimony whereof I have signed my name to this specification.

GEORGE X. WENDLING.
